FILM SPLICING APPARATUS

David L. Babcock, Rochester, N. Y., assignor to
 Eastman Kodak Company, Rochester, N. Y., a
 corporation of New Jersey

Application December 2, 1938, Serial No. 243,605

5 Claims. (Cl. 154—42)

The present invention relates to a cinematographic film splicing apparatus, and more particularly to the hinged connection for the film clamp associated therewith.

One object of the present invention is to provide a film splicing apparatus which is simple and efficient in operation, and which can, above all, be produced at low cost. Another object is to provide such a splicing apparatus with one or more hinged film clamps the hinged structure of which is simple to correspond with the low cost of the complete splicing apparatus, but which is efficient in operation. And another object is to provide a hinged structure for the film clamp, all of the parts of which, except a single spring member, are integral with the hinged parts and are stamped out with said parts. And a further object is to provide a hinged structure of the type described, the parts of which can be assembled practically without the use of tools and securely interlock with one another. And another object is to provide a hinged structure where the hinged parts are held in their assembled positions by a spring member which in turn serves as pintle bearings for the film clamp. And another object is to provide a hinged structure of the type described wherein said spring member in combination with cam portions on the hinged part integral with the film clamp normally acts to force said clamp toward its film holding position when the same is moved from its raised position, and which exerts a clamping pressure on said clamp when the same is in its film holding position.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing in which,

Fig. 1 is a plan view of a film splicing apparatus, showing the film clamps, hinged in accordance with the preferred embodiment of the invention, in their clamping positions relative to the base and holding the cutting and scraping tool.

Fig. 2 is a plan view of the film splicing apparatus showing one film clamp raised, and one film clamp lowered, and showing a film strip positioned on the base for the cutting operation.

Fig. 3 is a section taken substantially on line 3—3 of Fig. 2.

Fig. 4 is a section taken substantially on line 4—4 of Fig. 2.

Fig. 5 is an enlarged plan view of that portion of the splicing apparatus including the hinged structure for one of the film clamps, and showing the clamp in its clamping position, and

Fig. 6 is an elevation of the cutting and scraping tool adapted for use with the splicing apparatus.

Like reference characters refer to corresponding parts throughout the drawing.

Referring now to the drawing, wherein a preferred embodiment of the invention is shown, the splicing apparatus as a whole comprises a base plate 10 the edges of which are turned down, as indicated at 11, to provide legs which support the base plate proper from a table or like support on which the apparatus might be positioned. This apparatus is portable, but the plate is provided with two countersunk openings 12 through which screws may be passed if it should be desired to mount the apparatus onto a table or like support. The top of the base plate may be provided with a plurality of film engaging pins 13 spaced from one another longitudinally of the base plate by distances equal to the spacings of the perforations in a cinematographic film strip F, see Fig. 2, whereby said pins are adapted to engage said film perforations to locate the film longitudinally of said base plate. Although only one row of these pins 13 has been shown, whereby the film is engaged only at one margin, two rows of such pins may be provided, as is well known in the art, so that both margins of film will be engaged. The film strip F is held in engagement with the pins 13 by one or more film clamps 14 which are hinged to the base plate 10 at one side of the locating pins 13 to be brought down upon the film strip F positioned on said pins and engage the same adjacent said pins to hold the film strip thereon, see Fig. 2, or to be raised to permit a film to be placed on or removed from said pins. To permit the film clamp 14 to engage the film F, the same is provided with an aperture 15 through which the pins 13 extend when the clamp is in its film holding position.

To provide a proper cutting of the film strip F, the base plate 10 is provided with two elongated slots 16 and 17 which extend transversely of the base plate and across the film path thereon. The outside edge of each of these slots 16 and 17 provides a shearing edge along which the film is cut when the cutting and scraping tool 18, see Fig. 6, which is equal in thickness to the width of said slot, is inserted edgewise into each slot with

the end 19 thereof extending through the slot at one end thereof and at an acute angle to the base plate so that its arcuate portion 20 will engage the under side of the base plate 10 at the end of the slot and act as a fulcrum point about which the tool can be pivoted downwardly toward the base and through the slots to cut the film along the shearing edge of each of the slots.

After the two film ends have been trimmed as described, the scraping and cutting tool is reversed end for end and the nose 21 on the end thereof is inserted in the slot 16 with the scraping edge 22 of the tool overhanging the shearing edge of said slot, after which the tool is reciprocated in the slot across the surface of the film and adjacent thereto to remove the emulsion from the film. The nose 21 is equal in width to that of the slot 16 so that when the same is inserted therein no sideway movement of the tool will ensure, and the scraping edge 22 is equal to the amount of overlap which the film splice will have so that the correct width of emulsion is removed from the film strip thereby. The end of the tool 18 is cut away as indicated at 23 so as to permit of the nose 21 extending into the slot 16 to serve as a guide for the scraping edge as described. After the film ends have been trimmed and the emulsion has been removed from the end of one as described, cement is applied to the scraped film end and the other film end is removed from its locating pins 13 and replaced on said pins after being advanced longitudinally of the base toward the slots one perforation. Due to the positions of the two shearing edges of the slots 16 and 17 relative to each other and the locating pins 13 this single perforation advance of the one film end will give the desired overlap for the splice which will be equal to the width of emulsion scraped from the other film end. Pressure may be applied to the splice in any suitable manner during the time the cement is drying, and one way of inducing this pressure would be to lay the tool flatwise across the splice and press down thereon.

The splicing apparatus as a whole or its method of operation forms no part of the present invention, but is shown and described to point out one form of splicing apparatus which could be produced at a low cost. The present invention is concerned with providing a novel hinge structure for the film clamp 14 which will function efficiently, namely, act to hold the film clamp in a raised position, act to move the film clamp toward its clamping position when released from said raised position, and act to apply pressure to the clamp when the same is in its film holding position, and still be cheap to produce so that the total cost of the splicing apparatus will not be substantially increased due to its incorporation thereon.

Coming now to the invention, each film clamp 14 is provided at its rear end with a pair of spaced downwardly depending ears 25 which extend through a pair of slots 26 in the base plate 10 adjacent one down turned edge thereof. These ears 25 may be stamped out with the film clamp 14 and turned down afterward to make for low cost production. Each ear 25 is provided with a pintle recess 27 which is adapted to be located below the base plate when the ear is placed in its respective slot 26. A double ended spring member 28 is positioned so that its intermediate portion 29 is situated between the under side of the base plate 10 at the rear of the slot 26 therein and a boss 30 formed in the down

turned edge 11 of the base plate. The ends 31 of this spring member 28 are turned outwardly as shown, see Fig. 5, to engage the pintle recesses 27 and act as pintle bearings for the film clamp. The width of the slot 26 is made substantially equal to the thickness of the ear 25 so that no appreciable movement of the ears transversely of the slots can take place, and the ends 31 of the spring member 28 extend transversely across said slots to prevent the ears from being slid off the ends thereof.

To assemble this hinge, the ears 25 are inserted into the slots 26 and the clamp is turned to its upright position, see Fig. 3, where the open ends 15 of the pintle recesses 27 are directed toward the boss 30. The intermediate portion 29 of the spring member 28 is then located against the turned down edge 11 between the under side of the base plate 10 and the boss 30 after which the ends of the spring member may be retracted by a special tool until they snap into said pintle recesses. The inherent resiliency of the spring member 28 will serve to hold the parts in this assembled position, and the spring member will normally force the ears 25 longitudinally of the slots 26 so that the forward edge 32 of each of said ears will be pressed into engagement with the base plate 10 at the end of its respective slot 26.

It is desirable that the film clamp will normally be moved to its clamping position when the same is not in its upright position, and that the same, when in its film holding position, will exert a pressure on the film strip. The hinged structure is so formed and arranged that these functions are performed by the hinge structure itself. The forward edge 32 of each ear 25 is formed so as to provide a fairly steep cam portion 35, a gradual cam portion 36 continues with said cam portion 35, and a break 37. Referring now to Fig. 3, when the film clamp 14 is in its full raised position the break 37 in the edge 32 of the ear 25 will be above the lower corner 38 of the base plate at the end of the slot 26 and the force of the spring member 28 being applied slightly below said base in this position will tend to hold the film clamp in its raised position, or even tend to rotate it further back about the pintle bearings. Backward movement of the film clamp 14 is limited, however, by the engagement of the rear edge 39 40 of the clamp with that portion of the top of the base plate 10 between the slots 26.

Now when the clamp 14 is moved downwardly from its upright position enough to bring the cam portion 36 into engagement with the corner 38 at the end of the slot 26, the force of the spring member 28 will tend to force said cam portion against said corner in the manner of a wedge, and the cam portion will resolve this spring pressure into a component force which will tend to rotate the clamp to its holding position. The strength of this component force will, of course, depend upon the angle between the cam portion and the corner 38, and since in this first part of the clamp movement the force required need only be sufficient to cause rotation of the clamp about its pintle bearings this cam surface may be gradual. When the clamp has rotated nearly to its holding position, the cam portion 35 comes 45 into engagement with the corner 38, and since this cam portion is at a fairly steep angle with respect to said corner 38, the component force of the spring pressure resolved thereby will be considerably stronger than that resolved by the cam portion 36, whereby the clamp will be

snapped to its film holding position through this last part of its movement. The cam portion 35 is in effect a straight portion at a fairly steep angle to the corner 38 so that the force of the spring member intended to press the ear under the corner in the manner of a wedge will be resolved into a component force of appreciable strength which will tend to rotate the clamp about its pintle bearings. Referring to Fig. 4, it will be noticed that when the clamp 14 is in its film holding position the corner 38 has not reached the end of the cam portion 35. Due to this fact, the spring member will constantly tend to force the ears 25 under the corner 38, even when the clamp is in its film holding position, so that there will be a component force tending to rotate the clamp about its pintle bearings when the same is in its film holding position, which force will give the desired pressing action of the film clamp on the film strip.

That portion of each of the film clamps 14 adapted to overlie the picture area of the film strip when in holding position may be raised as indicated at 40 so that when not in use the tool 18 may be slid under the clamp between the same and the base plate 10, as shown in Fig. 1, for the purpose of keeping the complete apparatus intact or for packing purposes. The free ends of the film clamp may project beyond the edge of the baseplate 10, as indicated at 41, so that they may be easily grasped by the operator to be raised.

It will be apparent from the above description that the novel hinge structure for the film clamp can be produced at low cost in keeping with the complete splicing apparatus, and since the parts thereof are integral with the parts of the apparatus, with the exception of the spring member, they can be stamped out at the same time as said parts, thereby eliminating separate operations which are costly in production. Further, the ease with which this hinge structure can be assembled cuts down any assembly charge per unit almost to nothing. Although this hinge structure is very simple and can be produced at low cost, it nevertheless is efficient in operation. It is adapted to hold the film clamp in its full raised position, move the same toward its holding position when moved from said full raised position, and finally it is adapted to apply pressure to the film strip when in its film holding position, all features desirable of a film clamp on a splicing apparatus, and all of which features are only found in more expensive and more complicated hinge structures.

Although I have shown and described a certain specific embodiment of my invention, I am fully aware that many modifications thereof are possible. My invention, therefore, is not to be restricted except insofar as is necessitated by the prior art and by the spirit of the appended claims.

Having thus described my invention what I claim is new and desire to secure by Letters Patent of the United States is:

1. A film splicing block comprising a base plate having a turned down edge, and provided with a pair of spaced elongated slots adjacent said turned down edge and extending away therefrom, means on said base plate for engaging and positioning a film strip for operations necessary to splicing, a clamp member for holding said film strip on said base plate, a pair of spaced ears depending downwardly from one end of said clamp member and each one thereof extending through one of said spaced elongated slots, means

for pivoting said clamp member to said base member and normally acting to move the same to its clamping position relative to the top of said base plate, said means including a double-ended spring hinge pintle, the intermediate portion thereof engaging said turned down edge between said slots, and each of the ends thereof engaging a portion of one of said ears extending below said base plate.

2. A film splicing block comprising a base plate having a turned down edge, and provided with a pair of spaced elongated slots adjacent said turned down edge and extending away therefrom, means on said base plate for engaging and positioning a film strip for operations necessary to splicing, a clamp member, a pair of spaced ears depending downwardly from one end of said clamp member, and each one thereof extending through one of said spaced elongated slots, each of said ears provided with a pintle recess located below said base plate, and a double ended spring member having its intermediate portion engaging that portion of said turned down edge between said slots, and its ends turned outwardly to engage said pintle recesses in said ears to provide pintle bearings for said clamp, whereby said spring member tends to force said ears into abutment with one end of said slots.

3. A film splicing block comprising a base plate having a turned down edge, and provided with a pair of spaced elongated slots adjacent said turned down edge and extending away therefrom, means on said base plate for engaging and positioning a film strip for operations necessary to splicing, a boss projecting inwardly from said turned down edge and located between said slots and spaced below the bottom of said base plate, a clamp member for holding said film strip on said base plate, a pair of spaced ears depending downwardly from one end of said clamp member, and each thereof extending through one of said slots, each of said ears provided with a pintle recess located below said base plate, and a double ended spring member having its intermediate portion engaging said turned down edge between the underside of said base plate and said boss, and its ends turned outwardly to engage said pintle recesses in said ears to provide pintle bearings for said clamp, whereby said spring member is held in its assembled position by its own resiliency which also normally holds each of said ears against one end of its respective slot.

4. A film splicing block comprising a base plate having a turned down edge, and provided with a pair of spaced elongated slots adjacent said turned down edge and extending away therefrom, means on said base plate for engaging and positioning a film strip for operations necessary to splicing, a clamp member for holding said film strip on said base plate, a pair of spaced ears depending downwardly from one end of said clamp member and each one thereof extending through one of said spaced elongated slots, each of said ears provided with a pintle recess located below said base plate, a double ended spring member having its intermediate portion engaging that portion of said turned down edge between said slots, and its ends turned outwardly to engage said pintle recesses to provide pintle bearings for said clamp, whereby said spring member normally forces one edge of each of said ears into abutment with one end of said slots, that edge of each ear abutting the end of said slots provided with a cam portion which when engaging the end of said slots resolves the force of said

spring member into a component force which tends to rotate said clamp into its clamping position about said pintle bearings, and which exerts a clamping pressure on said clamp member when the same is in its clamping position.

5. A film splicing block comprising a base plate having a turned down edge, and provided with a pair of spaced elongated slots adjacent said turned down edge and extending away therefrom, means on said base plate for engaging and positioning a film strip for operations necessary to splicing, a clamp member for holding said film strip on said base plate, a pair of spaced ears depending downwardly from one end of said clamp member and each one thereof extending through one of said spaced elongated slots, each of said ears provided with a pintle recess located below said base plate, a double ended spring member having its intermediate portion engaging that portion of said turned down edge between 20

said slots, and its ends turned outwardly to engage said pintle recesses to provide pintle bearings for said clamp, whereby said spring member normally forces one edge of each of said ears into abutment with the end of said slots, that edge of each ear abutting the end of said slots provided with a first cam surface which when engaging the end of said slots resolves the force of said spring into a component force which tends to rotate said clamp toward its clamping position about said pintle bearings, and a second cam portion continuous with said first cam portion, and which when engaging the end of said slots resolves the force of said spring member into a component force greater than that induced by said first mentioned cam surface, and which is adapted to snap the clamp into its clamping position and induce a constant pressure thereon while said clamp is in its clamping position.

DAVID L. BABCOCK.
